ATTACHMENT FOR BOBBIN WINDING MACHINES

Filed Nov. 1, 1928

UNITED STATES PATENT OFFICE

JAMES DANIEL JOYCE, OF PHILADELPHIA, PENNSYLVANIA

ATTACHMENT FOR BOBBIN-WINDING MACHINES

Application filed November 1, 1928. Serial No. 316,605.

This invention relates to bobbin winding machines, and has for its object to provide improvements in the bobbin positioning and retaining means.

- 4 The bobbins employed in connection with the class of machines to which this invention relates are constructed of a pulp composition somewhat similar if not the same material as is commonly defined as "paper pulp board." 10 In the continued winding and unwinding of these pulp composition bobbins, the retaining caps heretofore applied to the upper end thereof tears and roughens the said end so as to in time render the bobbins unfit for use.

- 15 This invention consists in the construction of a bobbin retaining cap which protects the upper end of the bobbin against the tearing and roughening action, so that the life and usefulness of the bobbin is prolonged indefinitely and its efficiency preserved, as well as the elimination of the breaking or fraying of the yarn or thread in unwinding therefrom.

- 20 Referring to the accompanying drawing; Figure 1 is a reduced fragmentary and diagrammatic view illustrating a winding bobbin in operative position,

- 25 Figure 2 is an enlarged vertical sectional view through the bobbin and its retaining cap, and

- 30 Figure 3 is a view in perspective of the several parts of the retaining cap in their relative positions before assembly, and also illustrating them in association with the upper end of a bobbin to which the cap is to be applied.

- 35 Like numerals of reference indicate the same parts throughout the several figures, in which:

- 40 1 indicates the bobbin having the flared bottom portion 2 and the cylindrical body portion 3.

- 45 The lower flared end 2 passes over an annular upstanding flange 4 on the rotatable support 5. By this means the bobbin is supported and centered.

- 50 6 indicates a vertical winding spindle which is threaded at 7 at its upper end. The usual practice being to employ a left-hand thread so as to counteract the unthreading

moment due to the direction of rotation of the bobbin which moment would tend to unthread or loosen the cap if a right-hand thread was employed.

55 Referring particularly to the cap 8, it will be seen from Figure 3 that the same comprises a flange 9 having central opening 10 defined by a flat body portion 11 which merges into a gradually and downwardly curved outer portion 12. It will be noted that the upper end 13 of the bobbin 1 is curved substantially complementally to the curvature of the flange 9, as shown in Figure 2, so that the said flange 9 functions to exactly center the upper end of the bobbin 1 as shown in the drawings.

60 The knob portion 14 of the cap 8 is preferably formed of a material such as "bakelite" and includes a cylindrical knurled portion 15, a flanged portion 16 and a short depending cylindrical portion 17. A hole 18 (Figure 2) is centrally provided in the structure, and a threaded bushing 19 is pressed into said hole so that the end of the bushing is flush with the end of the depending cylindrical portion 17, as shown in Figure 3.

65 The cap also includes a collar 20 having a short upstanding annular flange 21 of smaller diameter than the hole 10 in the flange 9, the height of said flange 21 being slightly in excess of the thickness of the large metal flange 9, while the hole or bore 22 of the collar is of a size to provide a press fit over the depending portion 17 of the bakelite knob portion 14.

70 Having thus described the several parts of the invention the same are assembled as follows:

75 The threaded bushing 19 being pressed into the depending cylindrical portion 17 of the knob portion 14, said pending cylindrical portion 17 is passed through the hole 10 in the metal flange 9. The collar 20 is then pressed on the said depending cylindrical portion 17 until the short upstanding annular flange 21 passes through the said hole 10 in the metal flange 9 and bottoms against the flange portion 16 of the knob 14. This prevents the collar 20 from clamping the metal flange between the collar 20 and the flange 100

portion 16 of the knob 14, and permits free rotation of the knob 14 and its collar 20 with respect to the metal flange 9, but at the same time retains the metal flange 9 permanently in the assembly as will be seen from an inspection of Figure 2.

Having thus fully described the invention its operation is as follows:

- 10 The bobbin 1 being positioned on its support 5 as shown in Figure 2, the cap 8 is threaded on the end 7 of the stem 6. As soon as the metal flange 9 progresses downwardly and engages the end 13 of the bobbin it centers the said bobbin, and through 15 frictional engagement between the curved portion 12 of the said flange 9, and the curved end 13 of the bobbin, rotation of the said flange 9 on and against the end 13 of the bobbin is stopped, while the knob 14 of the 20 cap continues to be threaded down on the stem 6 until the said flange 9 tightly clamps the bobbin in proper operative position as shown in Figure 2.

25 By reason of this construction all rotation of the metal flange 9 on and upon the end 13 of the bobbin 1 is prevented, while a tight clamping action between the metal flange 9 and the end 13 of the bobbin is insured.

30 The result is that all tearing, scratching and roughening action on the end 13 of the bobbin is entirely absent and eliminated by the use of this construction, and the life and efficiency of the bobbin is thereby indefinitely 35 prolonged.

30 While I have shown and described what I conceive to be a preferred embodiment of the invention, I do not wish to be limited to the exact construction disclosed, but I 40 consider myself clearly entitled to all such changes and modifications as fall within the limit and scope of the appended claims.

What I claim as new and desire to secure by Letters Patent of the United States is:

- 45 1. A cap for centering and retaining a winding bobbin including a centrally bored knob portion which comprises a flange and a depending cylindrical portion, a threaded bushing within the bore of the knob portion, 50 a metal flange having a central hole, a flat central portion and a downwardly curved outer portion, and a collar which includes an upstanding cylindrical flange of smaller diameter than the hole in said metal flange, 55 the said upstanding cylindrical flange being of greater depth than the thickness of the said metal flange, the said collar being positioned on the said depending cylindrical portion of the knob portion with the said 60 metal flange therebetween, the said upstanding cylindrical flange on the said collar passing through the hole in the said metal flange and the bottoming against the flange of the knob portion to retain the metal flange without binding the same and to permit free

rotation of the knob portion with respect to the said metal flange.

2. A retaining and centering cap for winding bobbins including a centrally bored knob which comprises a flange and a depending cylindrical portion, a threaded bushing within the bore of the knob, a collar for the depending cylindrical portion, a metal flange having a central hole and an outer curved portion adapted to engage the end of a winding bobbin, the hole in the metal flange being of greater diameter than the depending cylindrical portion of the knob, said collar being disposed between the said flange of the knob and the said collar, the device including means to prevent binding the metal flange by the said collar and to permit free rotation of the said knob with respect to the said metal flange.

3. A retaining and centering cap for winding bobbins including a bored knob having threads therein and including a flange and a depending cylindrical portion, a collar for the cylindrical portion, a bobbin engaging flange interposed between the flange on the knob and the said collar and rotatable relatively to the said knob, the device including means for preventing the collar from binding against the said bobbin engaging flange.

4. A retaining and centering cap for winding bobbins including a threaded knob having a flange and a depending cylindrical portion, a collar for the cylindrical portion and a bobbin engaging flange interposed between the flange on the knob and the said collar and rotatable relatively to the said knob.

5. A retaining and centering cap for winding bobbins including a threaded knob having a depending cylindrical portion, a collar for the cylindrical portion, and a bobbin engaging flange interposed between the said knob and the said collar and rotatable relatively to the said knob.

6. A retaining and centering cap for winding bobbins including a threaded knob having a depending cylindrical portion, a bobbin engaging flange under the said knob and rotatable relatively thereto, and means for retaining the said bobbin engaging flange on the said knob.

7. A retaining and centering cap for winding bobbins including a threaded knob and a bobbin engaging flange and means for rotatably securing the said bobbin engaging flange on the said knob.

In testimony whereof I affix my signature.

JAMES DANIEL JOYCE.
